UNITED STATES PATENT OFFICE.

HOWARD C. ROOT AND JOHN C. REILLY, OF PHILADELPHIA, PA., ASSIGNORS
OF ONE-THIRD TO SAMUEL W. THOME, OF SAME PLACE.

DEVICE FOR SUSPENDING ELECTRIC CABLES.

SPECIFICATION forming part of Letters Patent No. 278,277, dated May 22, 1883.

Application filed September 2, 1882. (No model.)

To all whom it may concern:

Be it known that we, HOWARD C. ROOT and JOHN C. REILLY, both citizens of the United States, and residents of Philadelphia, Pennsylvania, have invented certain Improvements in Devices for Suspending Electric Cables, of which the following is a specification.

The object of our invention is to construct a device for effecting the rapid and secure attachment of electric cables to overhead wires; and this object we attain in the manner which we will now proceed to describe, reference being had to the accompanying drawings, in which—

15 Figure 1, Sheet 1, is a side view of the device; Fig. 2, a view of the end of the same, looking in the direction of the arrow, Fig. 1; Fig. 3, Sheet 2, a plan view; and Fig. 4, a longitudinal section.

20 In carrying on telephone-exchanges in large cities it has been found necessary to use large and heavy cables, each containing a number of wires, the cables being frequently covered with lead pipe, so that they are exceedingly heavy, and their proper support has been the cause of much difficulty. The plan now usually adopted is to first stretch a suspension-wire, and then to hang the cable upon this wire; and our invention has reference to a simple device for accomplishing this object in a rapid and effective manner.

In the drawings, A represents a block, through which extends an opening, a, the block being divided horizontally through the center 35 of this opening, and the two halves being held in place by a bolt, b, adapted to staples d, which project from the lower half of the block through openings in the upper half, the bolt being prevented from being accidentally displaced by 40 means of a spring-plate, e, which engages with a lug, e', on the upper half of the block, this plate, however, being readily freed from engagement with the lug when it becomes necessary to remove the bolt and separate the sections of the block, for a purpose described 45 hereinafter.

At the front end of the block A are bearings for the shafts or spindles of a grooved drum, B, and grooved roller D, and at the rear 50 end of the machine is a sleeve, F, adapted to

rotate upon the block, which is made of circular form at this point for the reception of the sleeve, the latter being retained longitudinally on the block by means of set-screws f, the points of which enter an annular groove in the block. The sleeve F is connected to the shaft i of the drum B by means of gearing comprising the spur-wheel g, pinion h, bevel-wheel m, and bevel-pinion n, so that as the shaft i rotates a rotating movement will be imparted to the sleeve F.

On the sleeve F are two radially-projecting arms, k, each of which is slotted for the reception of a threaded stem, p, on the spindle of a spool or bobbin, G, a nut, s, being adapted to the stem, so as to secure the spindle to the arm in any desired position. In the present instance we have shown only one spool; but each of the arms may, if desired, carry a spool; or one of the arms may have an adjustable weight 7c to act as a counter-balance for the spool as the sleeve F rotates.

The operation of the device is as follows: The wire x having been properly secured to its supports and the cable y attached to the same at one end, the two-part block is applied to the wire and cable, so that said wire and cable will pass through the opening a and between the drum B and roller D, as shown in Fig. 4. The sleeve F is then secured in position on the rear end of the block, and said block is drawn along the wire x in any suitable manner. The cable, which is drawn from a reel in the street or on an adjacent house-top, bears firmly upon the drum B, and as the latter is moved along beneath the cable a rotary motion is imparted to the drum and its shaft, which motion is transmitted through the medium of the gearing to the sleeve F, the rotation of which on the block causes the fine wire or wrapping from the spool G to be wound around the wire x and cable y, thus firmly binding the said cable to the wire. When the block reaches a point where the wire x is secured to a support the sleeve F is removed, and the halves of the block are separated, the device being again applied to the wire and cable in advance of the fastening.

We have shown the sleeve F as being made in halves hinged together and secured by a 100

pivoted bolt and nut; but this is not essential, as the sleeve might be slipped longitudinally from the block on loosening the set-screws *j*. The plan shown, however, is more expeditious and is preferred.

Instead of relying upon the friction of the cable upon the drum *B* to effect the rotation of the sleeve *F*, we may impart a positive movement to the latter. For instance, a drum, *J*, may be hung to bearings on the under side of the block *A*, as shown by dotted lines in Fig. 4, the shaft of this drum carrying the spur-wheel *g*, which gears into the pinion *h*, and a cord or wire, *w*, being wound around the drum and secured to any fixed object at its outer end, so that as the block is drawn along the wire *x* the said cord or wire *w* will be unwound, and the drum *J* will be rotated.

We claim as our invention—

1. The combination of the block *A*, having an opening and grooved guides for the supporting wire and cable, a sleeve, *F*, carrying one or more spools, *G*, and capable of rotation on the block, a driving-drum on a transverse

shaft, and gearing, substantially as described, whereby the movement of the drum is transmitted to the sleeve *F*, as set forth.

2. The combination of the block *A*, having an opening, *a*, the sleeve *F*, adapted to rotate on the block, the drum *B*, grooved for the reception of the cable, and having a transverse shaft, and gearing whereby the sleeve *F* is driven from the drum-shaft, as set forth.

3. The combination of the block *A*, made in two parts detachably secured together, and having an opening, *a*, the sleeve *F*, having a pinion, *n*, and also made in two parts detachably secured together, and gearing carried by the block and engaging with the pinion *n*, as set forth.

In testimony whereof we have signed our names to this specification in the presence of two subscribing witnesses.

HOWARD C. ROOT.
JOHN C. REILLY.
